Primary Examiner — Michelle E. Wilson*Assistant Examiner* — Clesce Moore, Jr.(74) *Attorney, Agent, or Firm* — Muncy, Geissler, Olds & Lowe, P.C.(57) **CLAIM**

I claim the ornamental design for a bicycle pedal crank, as shown and described.

DESCRIPTION

FIG. 1 is a top, front, right perspective view of a bicycle pedal crank showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom, rear, left perspective view thereof; and,

FIG. 9 is a top, front, right perspective view thereof, shown in use an alternative environmental configuration.

The broken lines in the drawings illustrate portions of the bicycle pedal crank which form no part of the claimed design.
